CHARLES STUART PARK, OF SAVANNAH, GEORGIA, ASSIGNEE OF ONE-HAID TO
MERRITT W. DIXON, JR., OF SAVANNAH, GEORGIA.

CLOSURE DEVICE FOR TANKS, &c.

1,220,267.

Specification of Letters Patent. Patented Mar. 27, 1917.

Application filed July 28, 1916. Serial No. 111,568.

To all whom it may concern:

Be it known that I, CHARLES S. PARK, a citizen of the United States, residing at Savannah, in the county of Chatham and 5 State of Georgia, have invented certain new and useful Improvements in Closure Devices for Tanks, &c., of which the following is a specification.

This invention relates to closure devices 10 for tanks and other receptacles, and the object of the invention is to provide simple means for securely fastening the cover over the neck or nipple of the receptacle, as more fully hereinafter set forth.

15 In the drawing:—

Figure 1 is a vertical sectional view of a tank neck or nipple, showing my closure device applied thereto.

20 Fig. 2 is a horizontal sectional view on the line 2—2 of Fig. 1.

Fig. 3 is a view similar to Fig. 1 with the cover removed, and

Fig. 4 is a side elevation in detail of the resilient clamp.

25 Referring to the drawing annexed by reference characters, *a* designates the neck or nipple of the tank or other receptacle, this neck being provided near its upper end, on its interior surface, with an annular inwardly-extending flange *b*, which is continuous except at one point in the circumference of the neck, at which point the flange is omitted to form a throat *c*, the two ends of the flange at this point being bevelled respectively upwardly and downwardly at *d*.

30 The cover *e* is provided at its underside with a circular projection *f*, which fits loosely within the neck *a* and is adapted to engage the flange *b* when the cover is moved to a closed position. Riveted or otherwise affixed to the underside of the cover is a metal disk *g* of sufficient diameter to extend nearly to the edge of the projecting part *f* of the cover. The edge of the disk 35 is bent away from the body-portion thereof and the bottom of the cover to form an annular outwardly-projecting clamp-flange *h*. This flange *h*, like the neck flange *b*, is continuous except at one point in its length, where it together with said body-portion is split radially to form a pair of resilient fingers *i*, one of which curves upwardly and the other downwardly, forming a throat-like passage *j* between the ends of the

40 fingers. The disk is also slotted on the line of connection between the flange and body-portion, said slot extending on both sides of the radial split and at right-angles thereto, so that the resilient fingers *i* are spaced from said body-portion and are connected only to the flange.

To lock the cover to the neck it is simply necessary to place it thereon, with its clamp flange *h* resting upon the flange *b*, and then turn the cover to the right, whereupon the downwardly turned finger *i* will engage under the bevel *d* which extends upwardly, and the continuous rotation of the cover will carry the flange *h* under the flange *b*, and thus draw the cover resiliently but tightly to its seat on the neck. A full turn of the cover is necessary to completely seat the cover, but continued turning in the same direction does not draw the cover any tighter to its seat nor does it tend to unlock the cover. To unlock and remove the cover, it is simply necessary to turn it to the left, whereupon the upwardly turned finger *i* will slide up over the upwardly-beveled part *d* of the flange *b* and thus cause the flange *h* to pass up through throat *c* and around on top of the flange *b* until the flange *h* throughout its entire length has passed up through the throat *c*.

45 It will be observed that an important characteristic of my device is its simplicity of construction and operation. It requires no arms or stops or threads, and is so constructed that the necessity of stepping the rotation of the cover at a certain point is eliminated. The elimination of screw-threads does away with the annoyance of catching the threads wrong and thus crossing or stripping the threads. My device 50 positively locks the cover in place by reason of the fact that the resilient flange is worked entirely under the rigid flange and thus eliminates the chance of it being shaken off.

55 It is obvious that my device may be used for a great variety of purposes. For example, it is capable of effective use as a plug or cover for automobile tanks, radiator tops, milk-cans, sugar-cans, barrels, tank-cars, electrical contacts and gasoline-tanks. It may in fact be used with any kind of cover or stopper or plug where a closure is needed which is not necessarily pressure-proof. My cover, it will be seen, is prac-

tically air and dust proof. It will be obvious also that the device can be stamped up from an integral piece of metal.

I claim:—

- 5 In a closure device, the combination with a neck having an internal rigid flange formed with a gap at one side of said neck, the opposing radial edges of the flange adjacent said gap being beveled downwardly
- 10 and upwardly to form inlet and outlet edges respectively, of a cover having secured to its underside a metal disk consisting of a body-portion and an annular outwardly projecting clamp-flange, said disk being
- 15 split radially through a portion of said

body-portion and said flange at one point thereof, and formed with a slot on the line of connection between said flange and body-portion to provide a pair of resilient fingers spaced from said body-portion and projecting toward each other and curved downwardly and upwardly to engage said inlet and outlet edges respectively, to guide said cover to closed and open positions.

In testimony whereof I hereunto affix my signature in the presence of two witnesses.

CHARLES STUART PARK.
